UNITED STATES PATENT OFFICE

158,427

BUILDING

Alfred O. Wupperman, Galveston, Tex.

Application September 14, 1948, Serial No. 148,576

Term of patent 14 years

(Cl. D13—1)

To all whom it may concern:

Be it known that I, Alfred O. Wupperman, a citizen of the United States of America, residing at Galveston, in the county of Galveston and State of Texas, have invented a new, original, and ornamental Design for Building, of which the following is a specification, reference being had to the accompanying drawing, forming part thereof.

Figure 1 is a front elevational view of a building showing my new design.

Fig. 2 is a rear elevational view.

Fig. 3 is a top plan view on a reduced scale.

I claim:

The ornamental design for a building, as shown.

ALFRED O. WUPPERMAN.
